UNITED STATES PATENT OFFICE.

JOHN R. SHOFFNER, OF DORA, PENNSYLVANIA.

TOOL FOR MINERS' LAMPS.

Application filed July 10, 1924. Serial No. 725,231.

To all whom it may concern:

Be it known that I, JOHN R. SHOFFNER, a citizen of the United States, residing at Dora, in the county of Jefferson and State 5 of Pennsylvania, have invented certain new and useful Improvements in Tools for Miners' Lamps, of which the following is a specification, reference being had to the accompanying drawings.

10 This invention relates to a tool for a miner's lamp and it is an object of the invention to provide a device of this general character embodying novel and improved means whereby the same may be employed 15 for digging refuse caked carbide from the bowl of the lamp and to afford a scraper for cleaning the corroded carbide from the threads of the lamp.

Another object of the invention is to provide 20 a novel and improved device of this kind which may be readily used as a screw-driver and as a pry to open the lid of the lamp when it sticks and to facilitate the putting in of new felts.

25 The invention consists in the details of construction and in the combination and arrangement of the several parts of my improved tool for a miner's lamp whereby certain important advantages are attained and 30 the device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:—

40 Figure 1 is a view in perspective illustrating a tool constructed in accordance with an embodiment of my invention and applied to the guard of a miner's cap;

45 Figure 2 is a view in perspective of my improved tool as herein disclosed;

Figure 3 is a view in side elevation with portions broken away of the tool as herein set forth.

As disclosed in the accompanying drawings, 50 my improved tool comprises an elongated and substantially flat member 1 formed of steel or kindred material and which has one end portion formed into a chisel edge 2 for use as a screw-driver and pry and also as a scraper for cleaning the corroded carbide from the threads of a

miner's lamp and for digging the refuse caked carbide from the bowl of the lamp. This last use is of particular advantage as it avoids the necessity of hammering the 60 lamp proper against hard objects as is now generally done resulting in injury to the lamp.

The opposite end portion of the member 1 is returned to provide a spring loop 3 the 65 outer end of which being continued by the elongated arm 4 positioned closely adjacent to the member 1 and in parallelism therewith, said arm 4 having its free end terminating a material distance inwardly of the 70 free end of the member 1 so as not to interfere when the member 1 is being used for the purposes hereinbefore referred to. It is also to be understood that the loop 3 constitutes a handle member to facilitate the 75 manipulation of the member 1. The outer or free end portion of the arm 4 is disposed on a slight outward curvature, as at 5, with respect to the member 1.

The arm 4 substantially midway its ends 80 has in swiveled connection therewith the tubular member or sleeve 6 in which is adapted to be inserted a drill case and also providing a reamer for the lamp tip.

The back of the member 1 preferably in 85 advance of the arm 4 has produced thereon the file surface 7.

When my improved tool is not in use, the same may be readily engaged with the guard G carried by the miner's cap, a marginal portion of the guard G being engaged between the member 1 and arm 4 as is clearly indicated in the accompanying drawings.

From the foregoing description it is 90 thought to be obvious that a tool for a miner's lamp constructed in accordance with my invention is particularly well adapted for use by reason of the convenience and facility with which it may be assembled and operated, and it will also be obvious that my invention is susceptible of some change and 95 modification without departing from the principles and spirit thereof and for this reason I do not wish to be understood as limiting myself to the precise arrangement and formation of the several parts herein shown in carrying out my invention in practice except as hereinafter claimed.

I claim:

1. A tool for use in connection with carbide lamps comprising an elongated member having one end portion returned to pro- 110

vide an overlying arm, the free end of the arm terminating a material distance inwardly of the free end of the member, the opposite end portion of said member being provided with a chisel edge.

2. A tool for use in connection with carbide lamps comprising an elongated member having one end portion returned to provide an overlying arm, the free end of the 10 arm terminating a material distance in-

wardly of the free end of the member, the opposite end portion of said member being provided with a chisel edge, the connecting portions of the member and arm constituting a spring loop, said loop also serving as a 15 handle.

In testimony whereof I hereunto affix my signature.

JOHN R. SHOFFNER.
